CLAIM

The ornamental design for a portable hose reel caddy, as shown.

DESCRIPTION

FIG. 1 is a front perspective view of a portable hose reel caddy showing our new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof; and,

FIG. 7 is a rear elevational view thereof.

The hose shown in FIG. 4 is shown broken away for ease of illustration.
